(57) CLAIM

The ornamental design for a jewelry mount, as shown and described.

DESCRIPTION

FIG. 1 is a perspective view from the front of the jewelry mount showing my new design;

FIG. 2 is a perspective view from the back thereof;

FIG. 3 is a first side view thereof;

FIG. 4 is a front view thereof;

FIG. 5 is a second side view thereof;

FIG. 6 is a back view thereof;

FIG. 7 is a top view thereof;

FIG. 8 is a bottom view thereof;

FIG. 9 is a front perspective view thereof, showing the jewelry mount in position on a strap; and,

FIG. 10 is a back perspective view thereof, showing the jewelry mount on the strap of FIG. 9.

The broken lines showing of environment are for illustrative purposes only and form no part of the claimed design.
